UNITED STATES PATENT OFFICE.

JAMES F. LOCKWOOD, OF PHILADELPHIA, PENNSYLVANIA, ASSIGNOR TO HIMSELF, THOMAS J. WHITNEY, AND ALVA BRYANT, ALL OF SAME PLACE.

DESIGN FOR A WHISK-HOLDER AND MATCH-SAFE.

SPECIFICATION forming part of Design No. 18,353, dated May 29, 1888.

Application filed April 26, 1888. Serial No. 272,001. Term of patent 3½ years.

To all whom it may concern:

Be it known that I, JAMES F. LOCKWOOD, a citizen of the United States, residing at Philadelphia, Pennsylvania, have invented a Design for a Combined Whisk-Holder and Match-Safe, of which the following is a specification.

My design is fully shown in the accompanying photographs, which illustrate slight changes in the detailed ornamentation without any change in the essential features of the design.

The design comprises the circular disk or plaque, upon the face of which are three pockets of tapering form and largest at the top, the center pocket being considerably larger in size than the side pockets, and having an open-work band at top and bottom and a projecting diamond-shaped panel in front. The groundwork of the disk or plaque is in imitation of hammered work, and the groundwork of the large central pocket in one of the designs illus-

trated is of the same character, while in the other design it is of a reticulated pattern. These variations in the minor details of the ornamentation, however, do not affect the essential similarity of the two designs. 25

I claim—

The within-described design for a whisk-holder and match-safe, said design consisting of the circular plaque or disk having on its face three tapering pockets, the central pocket being of considerably larger size than the side pockets and having on its face a projecting panel, all substantially as described and shown. 30

In testimony whereof I have signed my name to this specification in the presence of two subscribing witnesses. 35

JAMES F. LOCKWOOD.
